BICYCLE CHAIN GUARD

Donald A. Wolf, Dayton, Ohio, assignor to The Huffman Manufacturing Company, Miamisburg, Ohio, a corporation of Ohio

Filed Nov. 27, 1968, Ser. No. 14,686

Term of patent 14 years

Int. Cl. D12—11

U.S. Cl. D90—5

FIG-1

FIG-2

FIG-3

FIG-4

FIG-5

FIG-6

FIG. 1 is a side view of my new design for a bicycle chain guard;
 FIG. 2 is an enlarged side view thereof;
 FIG. 3 is a plan view thereof;
 FIG. 4 is a front end view thereof;
 FIG. 5 is a rear end view thereof;
 FIG. 6 is a rear view thereof;
 FIG. 7 is a side view showing a modified form of my new design for a bicycle chain guard;
 FIG. 8 is an enlarged side view thereof;
 FIG. 9 is a plan view thereof;
 FIG. 10 is a front end view thereof;
 FIG. 11 is a rear end view thereof;
 FIG. 12 is a sectional view taken along the line 12—12 of FIG. 13; and
 FIG. 13 is a rear view thereof.

The bicycle, partially shown in broken lines in FIGS. 1 and 7, is included for illustrative purposes only.
 I claim:

The ornamental design for a bicycle chain guard, substantially as shown and described.
